UNITED STATES PATENT OFFICE.

ROLAND STERLING DAVIDSON, OF WINNIPEG, MANITOBA, CANADA.

AUTOMATIC SPRINKLER.

1,228,412.

Specification of Letters Patent.

Patented June 5, 1917.

Application filed April 26, 1916. Serial No. 93,672.

To all whom it may concern:

Be it known that I, ROLAND STERLING DAVIDSON, a citizen of the United States of America, residing at the city of Winnipeg, 5 in the Province of Manitoba, in the Dominion of Canada, have invented certain new and useful Improvements in Automatic Sprinklers, of which the following is a specification.

10 This invention relates to sprinklers used for the protection of buildings from fire, and it relates more particularly to the means by which these are caused to automatically operate upon the occurrence of a fire in a 15 building in which they are installed. Prior to my invention sprinklers of the class to which this belongs depended for their operation upon a rise in the temperature of the surrounding air reaching a given point, such 20 being usually the fusing point of some metal used as a solder to connect certain parts of the apparatus upon the release of which the device was arranged to operate. My device differs from these in that a rapid rise only 25 of the temperature is necessary to automatically operate the sprinklers, and this rise, so that it be rapid, need not reach any particular degree of temperature. This difference in the mode of operation is particularly 30 valuable in the case of buildings having a low initial temperature, such for instance as cold storage plants, where the normal temperature is so low that great damage might be done by a conflagration before sufficient 35 heat resulted to operate the sprinklers of the older type.

The objects of the invention it is thought are clearly set out in the preceding paragraphs, and the means by which they are 40 attained will be found first described in the following specification, then more particularly pointed out in the appended claims and fully illustrated in the accompanying drawings forming a part hereof and in 45 which similar characters of reference indicate similar parts throughout the different views.

Referring to these—

Figure 1 is a side elevation of a sprinkler 50 embodying my invention.

Fig. 2 is a sectional view taken on the line 2—2 of Fig. 1.

Fig. 3 is a view showing the manner in 55 which the actuating members are connected with each other in one form of the device.

Fig. 4 is a section through the central actuating member.

Fig. 5 is the valve cap retaining strut.

Fig. 6 is the lever by which the cap retaining strut is maintained in position. 60

Fig. 7 is the detent or trigger which normally locks the cap retaining strut and lever in engagement.

Fig. 8 is a side elevation partly in section of a modified form of the invention. 65

Fig. 9 is a plan view of the body of the invention as illustrated in Fig. 8 and taken on the line 9—9 therein.

Fig. 10 shows a further modification of 70 the invention, and

Fig. 11 is a plan view of the same on the line 11—11 in Fig. 10.

In the drawings 1 indicates the body of the structure, this being provided with a portion 3 exteriorly screw-threaded for connection with the piping system furnishing liquid to the sprinklers, and hollow as at 4 in Fig. 2 to allow the said liquid to reach the valve 5 which is normally closed by the cap 6. 75

A yoke rises above the body of the device, the arms 7 and 8 of the yoke ending in a member 10 at the top adapted to support a deflector 12 extending therearound, the deflector and member 10 being apertured vertically and the latter interiorly screw-threaded for interengagement with the threads on a bolt 13 which passes down through both. 80

The valve cap 6 has a central raised portion 14 having a central depression 15 countersunk therein to receive the point 16 of the cap retaining strut 17, the said strut having its upper edge beveled back to provide a knife edge 18 adapted to engage in a groove 19 passing laterally across the under side of the lever 20, the upper side of the lever being formed with a vertically projecting point 21 adapted to enter a countersunk depression 22 in the end of the set-screw 13, the lever 20 also having a laterally extending arm 23. 90

The body of the device is provided with a flange 24 which may extend entirely around the said body or be formed on one side only 105 as in Figs. 1 and 2, the flange being shaped to provide a recess 25 having a groove 26 crossing the bottom thereof to receive a knife edged projection 27 formed on the lower end of the actuating detent or trig- 110

ger 28 vertically positioned to engage the under side of the arm 23 of the lever 20 adjacent the end thereof, the detent 28 thus becoming the power applied to the lever 20 5 fulcrumed at the point 21, to maintain the cap 6, (the load) through the strut 17, in closed position.

As the length of the detent 28 is a fixed quantity, adjustment of the set-screw 13 may 10 be required to bring the parts under proper tension, but after such adjustment it is usual to lock the set-screw against further movement by boring the head 10 and set-screw and pinning them together, thus preventing 15 tampering.

In the device as illustrated in Fig. 1 and kindred figures the detent 28 is provided 20 with a horizontal toe 29 extending out at the bottom, the said toe having a groove 30 crossing the top thereof. The actuating means in this case comprises three members indicated as 31, 32 and 33, rigidly connected at the top by a bar 34 or other suitable means, and vertically positioned above the 25 flange 24 to which the lower ends of the outer members 31 and 33 are secured at each side of the recess 25, the central member being thus suspended from the bar 34 with its lower end in the said recess 25 but out of 30 contact with the surrounding parts thereof.

The central member 32 is provided with an opening 35 adjacent its lower end for the reception of the toe 29 on the detent 28, the upper side of the opening being beveled back 35 to provide a downwardly facing knife edged projection 36 adapted to enter the groove 30 in the upper side of the toe 29.

It will be observed that the length of the central member from the bar 34 to the bottom of the knife edge 36 is intended to equal 40 that of the outer members 31 and 33.

The members 31, 32 and 33 may be of any 45 metal having a thermal absorptive tendency, and by reason of their correlation through the connections shown and the further fact that they are of equal mass and equal area, those 31 and 33 may be said to form one system while the suspended member 32 forms a second system, 50 the latter while equal to the others in length being of much greater area in proportion to its mass, as indicated by its increased width and decreased thickness in the drawings. Under these conditions it will be apparent 55 that equal temperature in both systems, such as would be produced by a gradual increase in temperature to almost any degree would result in an equal movement of all the members, which would necessarily be 60 upward and not calculated to affect the operative parts of the apparatus in any way; but on the other hand, should the rise in temperature be sufficiently rapid to bring about a differential movement of the two systems, 65 due to ability of the central member through

its greater area in proportion to mass, to absorb heat more quickly than the members of the opposite system, the greater movement of the central member will be exerted downwardly upon the toe 29 as a lever to remove the upper end of the detent or trigger 28 from engagement with the under side of the lever arm 23; the lever 20 releasing the strut 17 and allowing the freedom of the cap 6, the liquid retained thereby shooting 70 up against the under side of the deflector 12 and being distributed over a wide area.

It will be noted that owing to the inclination of the strut 17, the same when released, together with the lever 20, will be inclined to 80 fall away from the valve 5 and so will not impede the operation of the same.

The features of the device as shown in Figs. 8 and 9, in so far as the valve release is concerned, are precisely similar to those 85 previously described, these comprising the strut 17, lever 20 and trigger 28, the toe 29 on the latter being dispensed with however. The actuating members in this case are three metallic strips 37, 38 and 39 bent in circle 90 form and disposed one within the other, the members being bonded together at one end by the screw 40 which passes through all three and secures them to the casing of the valve 5, and at the opposite end by a stud or 95 rivet 41.

The outer members 37 and 39, the latter it will be noted being of much greater thickness than the former, are preferably of brass while the central member may be of nickel, 100 the device in this form depending for its operation upon the difference in the coefficient of thermal expansion of the two metals, and upon the difference in mass of the outer members formed from the same material. 105 Thus, if the rise in temperature be sufficiently gradual to allow of equal absorption by the outer and inner members 39 and 37 no operative movement will result, but if the rise in temperature be rapid the inner member will expand more quickly than the outer thus bringing about a distortion of the circle which the members describe resulting in the displacement of the trigger 28 and the release of the valve cap 6.

In the device as shown in Figs. 10 and 11, the expansion of a Bourdon tube 42 preferably metallic is made use of to displace the trigger detent 28, the tube being suitably supported from the flange 24 and horizontally positioned therearound so that the end 43 of the tube may come behind the detent 28. The end 44 of the tube is provided with a valve 45 having a small aperture entering the end of the tube and a rotary plug 46 by 120 means of which the size of the aperture may be regulated to permit of the escape of the surplus air during expansion due to a gradual increase of temperature, but not to permit the escape of all the surplus air due to 125 130

a rapid increase of temperature, thus creating a pressure in the tube under the latter circumstance calculated to straighten the same and displace the trigger detent 28.

5 A gas other than atmospheric air might be used in the device as will be easily understood, and an elastic container connected with the device to receive the surplus due to normal expansion and return the same to the 10 tube upon a fall in temperature, or a liquid might be used, but this is so obvious that it has not been considered necessary to illustrate such a connection.

From the foregoing description it will be 15 seen that the principle of operation is the same in the several variations of the device illustrated, that is to say, in each a plurality of parts are combined to form a single thermostatically operated unit, the heat engendered forces in which are in equilibrium during a gradual rise in temperature and the unit therefore operatively unresponsive, but which are differentially exerted under a 20 rapid rise in temperature to release the valve 25 retaining means.

Having thus fully described my said invention what I claim is:—

1. An automatic sprinkler comprising a 30 valve, means to maintain the valve normally in closed position, and means to release the valve retaining means, said last means comprising a plurality of parts connected to form a single thermostatically operated sys-

tem positioned and responsive to a rapid rise in temperature to release the valve retaining means but unresponsive to a gradual rise in temperature.

2. A sprinkler having a valve, means to maintain the valve in closed position, and means operated by a rapid rise in temperature to release the valve retaining means, said last named means comprising a flexible container supported from the body of the device and operatively engaging the valve retaining means, an orifice in the container communicating with the outer air, and means to control the size of the orifice whereby the same may be regulated so that a predetermined rate of increase in temperature will increase the pressure in the container to operate the valve release.

3. A sprinkler having a body, a valve, a strut having one end engaging the valve, a lever positioned to maintain the position of the strut, a trigger supported from the body 55 and engaging the end of the lever, and means operated by a rapid rise in temperature to actuate the trigger, thereby releasing the lever, strut and valve.

In testimony whereof, I affix my signature in the presence of two witnesses.

ROLAND STERLING DAVIDSON.
